UNITED STATES PATENT OFFICE

CHARLES E. BUCKBEE AND BARCLAY S. COCHRAN, OF WHITE BEAR LAKE, AND ESTHER M. JOHNSON, OF ST. PAUL, MINNESOTA, ASSIGNEES, BY MESNE ASSIGNMENTS, TO DANIELS MANUFACTURING COMPANY, OF RHINELANDER, WISCONSIN, A CORPORATION OF WISCONSIN

DESIGN FOR WRAPPING PAPER OR SIMILAR ARTICLE

Application filed October 3, 1931. Serial No. 41,300. Term of patent 7 years.

To all whom it may concern:

Be it known that CHARLES E. BUCKBEE, BARCLAY S. COCHRAN and ESTHER M. JOHNSON, citizens of the United States of America, and residing at White Bear Lake, White Bear Lake, and St. Paul, respectively, in the county of Ramsey and State of Minnesota, have invented a new, original, and ornamental Design for Wrapping Paper or Similar Article, of which the following is a specification, reference being had to the accompanying drawing, forming a part thereof.

The figure is a plan view of a piece of wrapping paper or a similar article showing a complete unit of the design, said unit being repeated in adjacent rectangles.

What we claim is:

The ornamental design for wrapping paper or similar article as shown and described.

CHARLES E. BUCKBEE.
ESTHER M. JOHNSON.
BARCLAY S. COCHRAN.
